UNITED STATES PATENT OFFICE.

GEORGE EATON, OF CLEVELAND, OHIO, ASSIGNOR TO MAY C. EATON, OF CLEVELAND,
OHIO.

DESIGN FOR AN ELECTRIC HEATER.

Application filed April 8, 1927. Serial No. 21,505. Term of patent 14 years.

To all whom it may concern:

Be it known that I, GEORGE EATON, a subject of Great Britain, residing at The St. Regis Apartments, Euclid Avenue and East 82d Street, in the city of Cleveland, county of Cuyahoga, State of Ohio, have invented a new, original, and ornamental Design for Electric Heaters, of which the following is a specification, reference being had to

the accompanying drawing, forming part thereof.

Fig. 1 is a side elevation and Fig. 2 is an end elevation of an electric heater showing my new design.

I claim:

The ornamental design for an electric heater, as shown.

GEORGE EATON.
